DIAPHRAGM PUMP

John H. V. Finney, Denver, Colo., assignor to
Mining Process and Patent Company, Denver,
Colo., a corporation of Delaware

Application September 7, 1942, Serial No. 457,533

13 Claims. - (Cl. 103—150)

1

This invention relates to diaphragm pumps and more particularly relates to pumps of the combination suction and pressure type.

Pumps of this general type utilize reciprocating mechanism producing alternate pressure and suction influences in a chamber in the pump with liquid expelled therefrom by pressure induced by the forward stroke of the mechanism and other liquid drawn in by suction induced by the return stroke. Suitable valve regulation controls the desired movement of liquid under these influences.

Single diaphragm pumps have not been suitable for this purpose because the diaphragm becomes concave on the suction stroke and convex on the pressure stroke, thus losing a large percentage of its displacement volume.

It is an object of the present invention to provide a double diaphragm pump, in which one diaphragm is utilized to effect the suction lift, while the other is utilized to develop the pressure head of the pump.

Another object of the invention is to provide actuating mechanism for a pump of the double diaphragm type by which rotary motion is converted into straight line reciprocating motion in a simple, efficient and economical manner.

Other objects reside in novel combinations and arrangements of parts and a novel mode of operation, all of which will be described in greater detail in the course of the following description.

To afford a better understanding of the invention reference will be made to the accompanying drawings illustrating a typical embodiment of the invention. In the drawings, in the several views of which like parts have been designated similarly.

Figure 1 is a top plan view of a pump embodying the features of the present invention;

Figure 2 is a vertical central section through the apparatus illustrated in Figure 1; and

Figure 3 is an end elevation of the pump housing illustrated in Figure 2, illustrating details of the assembly features.

The pump of the present invention is mounted on a suitable support or base 4, usually disposed horizontally, with a housing 5 supported at one end thereof, and actuating mechanism designated generally by the reference numeral 6 mounted on its opposite end.

The housing 5 has at its lower end an intake opening 7 the upper end of which provides a seat 7a for a ball 8, while the lower end of the intake passage is provided with means 9 for at-

2

tachment of a suitable fluid supply element (not shown) such as a hose.

A second passage 10, preferably having its lengthwise axis concentric with the axis of passage 7 extends from the upper side of housing 5 and the upper end of passage 10 has means 12 for connection with a suitable conductive element (not shown). The lower end of passage 10 also is provided with a seat 10a for a second ball.

10 The openings in the outer end of housing 5 are closed by sectional wall members 14, while the inner end of the housing terminates in an annular rim 15 shouldered at 16 to provide a seat for a diaphragm unit 17 which is bolted thereon as shown at 18.

The housing 5 also is provided with a pressure-equalizing passage 19, one end of which terminates in the intake opening 7 as indicated at 20, while the opposite end extends through the 20 diaphragm member 17 into the space 21 between two flexible diaphragm members 22 and 23, each of which is convex on the side in space 21 and concave on the opposite side, the purpose of which will be described hereinafter.

25 The diaphragm member 17 comprises an annular rim section 24 of generally U-shaped section, against the opposite sides of which the diaphragm members 22 and 23 are placed and held by two clamping rings 25 and 26. Bolts 30 27 hold these parts in their assembled relation.

An opening is provided in member 24 for admission of atmospheric air into the space 21 between the diaphragms 22 and 23, and a suitable valve 28 permits selective control of such 35 air admission.

The diaphragms are adapted for flexure through the provision of a movable clamping member designated generally by the reference numeral 29. This member comprises an end 40 plate 30 carrying a central stop member 31, a spacing ring 32 inserted between the diaphragms 22 and 23, and a second clamping ring 33, all of the same being held in place by bolts 34. The plate 33 in turn is connected to an end plate 45 35 carried on a crosshead 36 of actuating mechanism 6 by means of a bolt 37, the inner end of which abuts stop 31.

The actuating mechanism in this embodiment of the invention comprises a rotary shaft 38 journaled on support 4 and carrying an eccentric member 39 held for conjoint rotation by a key 40. A connecting rod 41 is attached to eccentric 39 by means of strap sections 42 and 43 held together by bolts 44.

55 The opposite end of connecting rod 41 has a

pivotal connection with a shaft 45, with which crosshead 36 also is pivotally connected. A second shaft 46 with which the extended end of crosshead 36 is pivotally connected projects through a slot 47 in connecting rod 41 permitting lateral movement of rod 41 relative to this shaft during the cycle of its movement by eccentric 39.

The crosshead 36 and its associated reciprocating member 29 are supported for movement substantially parallel to base 4 through the provision of two rocker arms 48 and 49, the lower ends of which are pivotally connected with two shafts 50 and 51 respectively, on base 4. The axes of these shafts are in the same horizontal plane and they are spaced the same distance as the axes of shafts 45 and 46 but in vertical relation are midway between the extreme range of movement of the associated shafts 46 and 45.

In operation the inlet 7 is connected with a suitable source of fluid supply through attachment of a conduit on means 9 and provision is also made for disposal of liquid discharged through outlet 10 by connection of a suitable conduit with attachment means 12.

The shaft 38 driven by a suitable prime mover (not shown) rotates the eccentric 39 with the result that an oscillating movement is imparted to shaft 45 on which the end of connecting rod 41 is mounted.

Through the arrangement of pivotal supports for crosshead 36, movement of shaft 45 imparts a substantially straight line motion to the end of crosshead 36 carrying diaphragm member 29, with the result that the diaphragms 22 and 23 are moved one way during the forward stroke and in an alternate way during the return stroke.

This diaphragm assembly provides with walls of housing 5 an enclosure for a pressure chamber 52 extending between inlet 7 and outlet 10. The return stroke with the resulting movement of the diaphragms serves to exert suction upon ball 8 to raise it from its seat and causes liquid to be elevated through intake 7 and enter chamber 52.

Similarly, this suction action causes ball 13 to rest tightly against its seat 10a until commencement of the forward stroke, whereupon pressure resulting from the changed position of the diaphragms returns ball 8 to its seat 7a and elevates ball 13 from its seat, with the result that liquid in chamber 52 is forced through outlet 10 and its associated conduit.

In the aforesaid action, the return stroke causes a flexure of diaphragm 22 which creates a vacuum in the suction line through equalizing passage 19 drawing liquid up toward the pump. On this stroke, the inner diaphragm 23 merely follows along but does overcome the very slight additional vacuum required to raise ball 8 off seat 7a.

As a consequence of these actions during the return stroke the vacuum produced by outer diaphragm 22 with valve 8 open extends through space 21, equalizing passage 19, chamber 52 and in the suction line connected with intake 7. As the vacuum is essentially the same in space 21 and chamber 52, the inner diaphragm 23 has no tendency to change from its convex shape to a concave shape. Due to the vacuum so created liquid flows in through intake 7 filling equalizing passage 19 and space 21 as well as chamber 52.

On the forward stroke, inner diaphragm 23 alone forces the liquid in chamber 52 past ball 13 and through outlet passage 10. In this action outer diaphragm 22 merely follows along. However, vacuum is maintained in space 21 during this stroke, due to the weight of the column of

liquid beneath intake 7 exerted through equalizing passage 19.

Thus on both the forward and return strokes the outer diaphragm 22 is under a partial vacuum, and as the space 21 between the diaphragms is substantially uniform at all times there is little or no flow of fluid through equalizing passage 19 during normal operation.

It also is intended to permit additional control of the suction action by introduction of air into space 21 between the diaphragms. For this purpose a valve 28 communicates with the atmosphere through the wall of rim member 24, and this valve can be adjusted to admit a selective volume of air into the space 21. A petcock-type valve has been illustrated but it will be understood any suitable valve mechanism performing the same function may be substituted in place thereof.

By reason of this combination and arrangement of parts, the following advantages are derived:

1. The outer diaphragm does the work of lifting the liquid to the pump.

2. The inner diaphragm does the work of discharging the liquid from the pump.

3. There is at all times a partial vacuum on the outer diaphragm.

4. On the suction stroke there is no pressure on either side of the inner diaphragm while on the discharge stroke the pressure on the inner diaphragm is equal to the total head against which the pump is operating.

5. Slight variations in the volume between diaphragms as occur between mid stroke and extreme stroke, are compensated for by the free flow of liquid through the equalizing passage.

6. The direction of pressure on each of the two diaphragms is never reversed, and the greater pressure is always exerted against the concave side of each diaphragm. That is, during the suction stroke, the air pressure outside tends to exceed the pressure in space 21, but such excess pressure is exerted against the concave side of diaphragm 22. Also, during the pumping stroke, the pressure in chamber 52 exceeds the pressure in space 21, but is exerted against the concave side of diaphragm 23. Thus, both diaphragms tend to retain shape at all times, regardless of the direction in which the pump plunger is moving, and there is no tendency for either diaphragm to change from concave to convex or vice versa.

7. Since the pressure on the outer diaphragm is always inward, the failure of either diaphragm results in an inward leakage of air or an internal leakage and no liquid is spilled.

8. Regulation as to the amount of liquid being pumped can be effected by a valve 28 which permits more or less controlled leakage of air into the space between diaphragms.

9. While there is at all times a partial vacuum behind the outer diaphragm, slight leakages and the admission of regulation air into the space between diaphragms result in there being little or no actual liquid in the space between diaphragms. This results in a minimum of wear and abrasion on the diaphragms.

In many operations, it will be desirable to have a variable stroke reciprocating mechanism as the actuating mechanism of the pump and the present invention has been designed to embody such feature. In such event, a double eccentric may be substituted for the eccentric 39 illustrated in Figure 2, to effect the desired variations.

While any suitable form of valve and seat ar-

angement may be provided to control the flow of fluid through intake 7 and outlet 10, in the preferred arrangement illustrated in Figure 2 the seats are in the form of resilient gaskets 7a and 10a respectively, and balls of suitable size and weight are provided to seat thereon. However, various types of valves are employed for this purpose in the reciprocating pump art and it is within the intention of the present invention that such other valve control may be substituted where desired.

What I claim and desire to secure by Letters Patent is:

1. A pump of the character described, comprising a housing having an intake passage and a discharge outlet distant therefrom, two flexible diaphragms supported in spaced relation in the housing and defining with a wall of the housing a pressure chamber between the intake and the outlet, said diaphragms being in concave relation oppositely to each other throughout the stroke of the pump, there being a pressure-equalizing passage in the housing, one end of which extends to and is connected with the intake passage, and the other end of which terminates in the space between the diaphragms, a pressure-actuated valve for controlling the flow of fluid through the discharge outlet, a suction-actuated valve for controlling the flow of fluid through the intake passage, and reciprocating mechanism for flexing said diaphragms.

2. A pump of the character described, comprising a housing having an intake and a discharge outlet distant therefrom, two flexible diaphragms supported in spaced relation in the housing and defining with a wall of the housing a pressure chamber between the intake and the outlet, there being a pressure-equalizing passage in the housing, one end of which terminates at the intake and the other end of which terminates in the space between the diaphragms, means, including a valve, for admitting atmospheric air into the space between the diaphragms, a pressure-actuated valve for controlling the flow of fluid through the discharge outlet, a suction-actuated valve for controlling the flow of fluid through the intake, and reciprocating mechanism for flexing said diaphragms.

3. A pump of the character described, comprising a housing having an intake and a discharge outlet distant therefrom, two flexible diaphragms supported in spaced relation in the housing and defining with a wall of the housing a pressure chamber between the intake and the outlet, there being a pressure-equalizing passage in the housing, one end of which terminates at the intake and the other end of which terminates in the space between the diaphragms, means, including a manually-operable valve positioned outside the housing, for admitting atmospheric air into the space between the diaphragms in selective volume, a pressure-actuated valve for controlling the flow of fluid through the discharge outlet, a suction-actuated valve for controlling the flow of fluid through the intake, and reciprocating mechanism for flexing said diaphragms.

4. A pump of the character described, comprising a housing having an intake passage and a discharge outlet distant therefrom, two flexible diaphragms supported in spaced relation in the housing and defining with a wall of the housing a pressure chamber between the intake passage and the outlet, said diaphragms being in concave relation oppositely to each other throughout the stroke of the pump, there being a pressure-equalizing passage in the housing, one end of which

terminates at the intake passage and the other end of which terminates in the space between the diaphragms, a pressure-actuated valve for controlling the flow of fluid through the discharge outlet, a suction-actuated valve for controlling the flow of fluid through the intake passage, and variable stroke reciprocating mechanism for flexing said diaphragms.

5. A pump of the character described, comprising a housing having a lower intake and an upper discharge outlet, two flexible diaphragms disposed vertically in spaced relation in the housing and defining with a wall of the housing a pressure chamber between the intake and the outlet, said diaphragms being in concave relation oppositely to each other throughout the stroke of the pump, there being a pressure-equalizing passage in the housing, one end of which terminates at the intake and the other end of which terminates in the space between the diaphragms, a ball valve for controlling the flow of fluid through the discharge outlet, a ball valve for controlling the flow of fluid through the intake, and reciprocating mechanism for flexing said diaphragms.

6. In a pressure pump, inclusive of a suction line, a discharge line, and a pressure chamber, a closure for a side of said chamber comprising a pair of spaced diaphragm members mounted to maintain a concave relation oppositely to each other during movement together in opposite directions to create alternate pressure and suction influences in said chamber, said chamber having a conductive passage extending from the space between said diaphragms to a point in the suction line at the intake side thereof and subject to the suction influences of said line for reducing pressure between said diaphragms.

7. In a pressure pump, inclusive of a suction line, a discharge line, and a pressure chamber, a closure for a side of said chamber comprising a pair of spaced diaphragm members mounted to maintain a concave relation oppositely to each other during movement together in opposite directions to create alternate pressure and suction influences in said chamber, said chamber having suction-inducing means associated with said diaphragm members and constructed and arranged to act on matter in the space between said diaphragms and cause one said diaphragm to perform the lift and the other said diaphragm to perform the discharge of the pump.

8. In a pressure pump, inclusive of a suction line, a discharge line, and a pressure chamber, a closure for a side of said chamber comprising a pair of spaced diaphragm members mounted to maintain a concave relation oppositely to each other during movement together in opposite directions to create alternate pressure and suction influences in said chamber, said chamber having means associated with said diaphragms constructed and arranged to control the pressure and suction influences in the space between said diaphragms throughout the operating cycle and thereby hold the inner surfaces of said diaphragms in said concave relations.

9. In a pressure pump, inclusive of a suction line, a discharge line, and a pressure chamber, a closure for a side of said chamber comprising a pair of spaced diaphragm members mounted to maintain a concave relation oppositely to each other during movement together in opposite directions to create alternate pressure and suction influences in said chamber, and means associated with said pressure chamber for injecting liquid into and ejecting liquid from the space between the diaphragms to compensate for volu-

volumetric changes occurring between their mid-stroke and extreme-stroke positions.

10. In a pressure pump, inclusive of a liquid suction line, a discharge line, and a pressure chamber, a closure for a side of said chamber comprising a pair of spaced diaphragm members mounted for movement together in alternate opposite directions to create alternate pressure and suction influences in said chamber, and means associated with said pressure chamber for injecting air into and ejecting air from the space between the diaphragms to compensate for volumetric changes occurring between their mid-stroke and extreme-stroke positions.

11. In the art of pressure pumps in which spaced diaphragm members forming an enclosing wall of a pressure chamber are mounted for movement in opposite directions to create alternate suction and pressure influences in said chamber, the improvement which comprises means for injecting and ejecting air into the space between the diaphragms to compensate for volumetric changes occurring between their midstroke and extreme-stroke positions, and means separate from said injecting and ejecting means for continuously introducing air into the space between the diaphragm members.

12. In a pump having an inlet passage and an outlet passage and a pumping chamber therebetween, a reciprocable crosshead; a pair of flexible diaphragms connected with said crosshead and forming with said crosshead a movable wall of said chamber, said diaphragms forming a space therebetween and each diaphragm being convex on the side nearest to the other diaphragm so as to extend a substantial distance toward the other diaphragm; and means connecting the space between said diaphragms with said inlet passage.

13. In a pump having an inlet passage and an outlet passage and a pumping chamber therebetween, a reciprocable crosshead; a pair of flexible diaphragms connected with said crosshead and forming with said crosshead a movable wall of said chamber, said diaphragms forming a space therebetween and each diaphragm being convex on the side nearest to the other diaphragm so as to extend a substantial distance toward the other diaphragm; means connecting the space between said diaphragms with said inlet passage; and means for reciprocating said crosshead along a substantially straight line.

JOHN H. V. FINNEY.
